(57) **CLAIM**

The ornamental design for a built-in kiosk, as shown and described.

DESCRIPTION

FIG. 1 is a top, front, right side perspective view of a built-in kiosk, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom, rear, right side perspective view thereof;

FIG. 9 is a top, rear, right side perspective view thereof;

FIG. 10 is a reference perspective view thereof showing environment of the built-in kiosk; and,

FIG. 11 is another reference perspective view thereof showing a configuration of use.

The broken lines in FIGS. 10 and 11 show environmental subject matter that form no part of the claimed design.
